(57) **CLAIM**

The ornamental design for a stabilizing transport cushion, as shown and described.

DESCRIPTION

FIG. 1 is a perspective view of a stabilizing transport cushion showing our new design;

FIG. 2 is a perspective side view of the stabilizing transport cushion;

FIG. 3 is a front view of the stabilizing transport cushion;

FIG. 4 is rear view of the stabilizing transport cushion;

FIG. 5 is a left-side view of the stabilizing transport cushion;

FIG. 6 is a right-side view of the stabilizing transport cushion;

FIG. 7 is a bottom view of the stabilizing transport cushion;

FIG. 8 is a top view of the stabilizing transport cushion;

FIG. 9 is an enlarged view of area 9 shown in FIG. 8;

FIG. 10 is an enlarged view of area 10 shown in FIG. 8;

FIG. 11 is a perspective view of the stabilizing transport cushion in an inclined configuration showing an unclaimed indentation along the top surface resulting from a patient positioned on the top surface; and,

FIG. 12 is a perspective view of the stabilizing transport cushion in use, positioned on an unclaimed stretcher device. The short dash broken lines in the drawings depict portions of the stabilizing transport cushion that form no part of the claimed design. The longer dash broken lines in FIGS. 11-12 depict environmental subject matter and form no part of the claimed design. The dot dash broken lines in the drawings depict a symbolic break within the stabilizing transport cushion and any feature within the break lines form no part of the claimed design. The dot dot dash lines depict boundaries of the enlarged views and form no part of the claimed design.
